[57] **CLAIM**

The ornamental design for a tire tread and buttress, as
shown and described.

DESCRIPTION

FIG. 1 is a perspective view of a tire tread and buttress
showing my new design;

FIG. 2 is a front elevational view thereof;

FIG. 3 is a side elevational view thereof; and,

FIG. 4 is an enlarged fragmentary front elevational
view thereof.

The pattern is understood to be repeated uniformly
throughout the circumference of the tire tread and but-
tress.

The broken line showing of the tire sidewall in all views
of the drawing is for illustrative purposes only and
forms no part of the claimed design.
